UNITED STATES PATENT OFFICE.

JAMES HENRY HINCH, OF LACONIA, ASSIGNOR OF THREE-FOURTHS TO
WALTER HENRY PHILBRICK, OF BELMONT, NEW HAMPSHIRE.

HYDRAULIC MOTOR.

SPECIFICATION forming part of Letters Patent No. 291,189, dated January 1, 1884.

Application filed September 1, 1883. (No model.)

To all whom it may concern:

Be it known that I, JAMES H. HINCH, of Laconia, in the county of Belknap and State of New Hampshire, have invented an Improved 5 Hydraulic Motor; and I do hereby declare that the following is a full and exact description thereof, reference being had to the accompanying drawings, making part of this specification.

10 My invention is especially intended for small motors for driving sewing-machines and other light work, but may be applied to motors of larger size, if desired.

15 The invention consists of several special features of construction, which I shall specify in order, referring to the said drawings, in which—

20 Figure 1 represents a top view of the hydraulic motor; Fig. 2, a central vertical section of the same; Fig. 3, a top view of the lower section of the motor-case; Fig. 4, a bottom view of the motor-wheel, and Figs. 5, 6, and 7, views of parts in detail.

Like letters designate corresponding parts in all the figures.

25 First. In the construction of the case I have the following special features: The case is cast in two parts, A and B, joined horizontally at the periphery, and nearly centrally between top and bottom. These parts have flanges a b

30 at their joining edges, with packing c between, and secured together by bolts d d. Thus the case is made water-tight, so that it may be used in a dwelling without leakage. The water is to be let into the case through the top part, A, 35 which is provided with an aperture, or, preferably, two apertures, having enlargements f f around them, to give sufficient bearing for the pipes or nozzles C C, fitting into the apertures water-tight. The water after use is dis-

40 charged through an aperture, g, in the bottom part, B, into which aperture a discharge-pipe, D, fits. The bottom part, B, has a suitable base, h, to sustain the case upon or attach it to a table or other suitable support. The upper bearing, i, for the wheel-shaft is formed on a yoke, E, secured to the top part, A, of the case. The lower bearing, j, is located inside of the case, and is formed on a bridge-tree, G, which has slots k k near its ends, which are supported

50 on lugs m m, cast upon the inner surface of the bottom part, B, of the case. Screws n n are passed down through the slots in the bridge-tree into these lugs, and by this means the bearing j is adjusted to an exactly central position, as required. The shaft H of the wheel 55 passes through a central aperture in the top part, A, there being a suitable enlargement, o, around it, in which the aperture may be provided with a suitable packing around the shaft, if necessary.

60 Second. I mount the wheel-shaft H, which is properly made of steel hardened at the bearing ends, between two conical hardened bearings, i j, the ends of the shaft having conical cavities to receive the bearings, and I have 65 these bearings made to screw up or down in the yoke and bridge-tree holders, so that not only can the bearings be adjusted to compensate for the wear, but the wheel can thereby be adjusted up and down to adapt it to the precise 70 position in relation to the water-applying nozzles which will produce the best effect and obtain the largest percentage of power from the water. The wheel thus mounted runs with the least possible friction, thereby utilizing 75 the power to the fullest extent.

Third. I construct the water-wheel I in a peculiar manner. I first cast the body of the wheel in a single piece with an enlarged rim, r, for the double purpose of adding weight and 80 consequent momentum to the wheel, that it may run evenly and steadily, and furnishing sufficient width of peripheral bearing to apply the buckets s s thereto. The buckets are made of thin sheet metal swaged into the proper form, 85 substantially as shown, and inserted into oblique cuts in the periphery of the wheel, as shown most clearly in Figs. 6 and 7. For small motors I cast the wheel in brass or similar alloy which will not corrode in the water, 90 and therefore will not clog up the wheel with rust, nor make the weight uneven on different sides. This material is also more easily worked, particularly in cutting the slots or kerfs for the buckets, than iron would be. The buckets s s 95 may be made also of brass or other alloy having similar properties. The buckets are arranged at short intervals around the periph-

ery of the wheel, the kerfs in which they are secured being at an angle of about forty-five degrees to the horizon. The outer edges are curved backward, and their upper edges are first curved downward and then upward, while their lower edges are best curved first upward and then downward, thereby widening the buckets considerably beyond the depth of the periphery of the wheel. The water from the nozzles strikes these buckets at an angle approximating forty-five degrees from the radial lines of the wheel, or about midway between the radial and tangential lines, which direction is believed to be the most effectual for a turbine wheel of such a construction as above specified.

Fourth. The water is introduced into the case and let onto the wheel through a nozzle, C, of peculiar construction. It fits tightly in the bearing *f* of an aperture in the top case, and reaches down nearly to the top of the wheel. Near the lower end it curves laterally, so as to direct the water against the buckets of the wheel, as above specified. The ajutage of the nozzle is contracted, as shown in Fig. 5, by which the stream of water is concentrated on the buckets just at the points where it will have the best effect. The outer end, *t*, of the nozzle is formed with a suitable coupling for a water-pipe or hose-pipe. One nozzle will serve for driving the wheel; but I prefer to employ two, on opposite sides of the wheel, as shown in the drawings, so that the two streams of wa-

ter shall balance each other in their strain upon the wheel, and thereby obviate much friction and wear.

This motor is compact, strong, and efficient, and can be used almost anywhere, and readily changed from one place to another. It runs, as above indicated, with very little friction, and utilizes a high percentage of the water-power. It is also simple and cheaply made.

I claim as my invention—

1. A water-wheel case cast in two parts, A and B, with water-inlet apertures in the top part and water-discharge aperture in the bottom part, provided with an outside yoke, E, for the upper bearing of the wheel-shaft, and an inside bridge-tree, G, for the lower bearing of the shaft, substantially as set forth.
2. The combination of the wheel-shaft II, having conical hollow journals at the ends, and screw-bearings *i j*, with the yoke E and bridge-tree G, substantially as set forth.
3. The combination of the water-wheel I, having the obliquely-set buckets *s s* secured around its periphery, with a nozzle, C, having a laterally-curved ajutage at its inner end, substantially as and for the purpose herein specified.

In testimony whereof I have signed my name in presence of two witnesses.

JAMES HENRY HINCH.
